SAFETY SWITCH

Ernest M. Miller, Excelsior, Minn., assignor to
Minneapolis-Honeywell Regulator Company,
Minneapolis, Minn., a corporation of Delaware

Original application May 4, 1936, Serial No.
77,758. Divided and this application October
25, 1937, Serial No. 170,758

18 Claims. (Cl. 200—122)

This invention relates broadly to a safety switch and more particularly to a switch which will assume an open contact position after a certain time interval.

This switch is adapted for use in an oil burner control system but is not necessarily limited to such use, it being distinctly understood that it may readily be used for other purposes.

One object of this invention is to provide a switch which will automatically shut down an oil burner system a predetermined time after it has been started if ignition has failed to take place.

Another object of the invention is to provide a time switch comprising a bimetallic element which is actuated by a heater to trip a latch to cause the switch to open.

Another object is to provide a switch of the above type wherein the bimetallic element is compensated for variations in ambient temperature.

Another object is to provide a switch which will open automatically at the end of a given time interval, and means for adjusting the length of this time interval.

Still another object is to provide an automatic switch which will open after a predetermined time interval and wherein a means is provided for manually resetting the device.

A further object of the invention is to provide a switch which will automatically trip to open position upon the occurrence of a predetermined condition by means of a thermostatic latch, and which cannot be closed by the manual reset mechanism until the thermostatic latch is in a position to hold the switch closed.

A further object of the invention is to provide a switch of the above type wherein the switch will not close until the latch has been reset and the manual means released.

A still further object is to provide a safety switch requiring a manual reset wherein the main stress exerted on the spring contact arms is exerted thereon by the manual reset lever which has a very limited motion whereby said spring contact arms are saved from undue stress and strain.

Other objects will become apparent to those skilled in the art as the specification is considered having reference to the accompanying drawings in which:

Figure 1 is a side elevational view of the switch, parts of the supporting structure being shown in section;

Figure 2 is a view taken along the line 2—2 of

Figure 1 and looking in the direction of the arrows;

Figure 3 is a perspective view of certain portions of the structure shown in Figure 2 in a different operating position; and

Figure 4 is a detail view showing the thermostatic latch and electric heater therefor and taken on the line 4—4 of Figure 2.

This application is a division of my co-pending application serial number 77,758, filed May 4, 1936, now Patent 2,175,720.

The switch mechanism is all mounted upon an insulating panel 10 and supported by a mounting bracket 11 which has at one extremity a downwardly depending portion 12 and at the other extremity a second downwardly depending portion 13. As better shown in Figure 3, portion 13 has an aperture 14 therethrough. A pair of spring leaf contact members 15 and 16 is carried by bracket 11 and secured thereto by screws 17, which pass through an insulating panel 18 and relatively large apertures in flange 12 into panel 10, and thus serve not only to support contact members 15 and 16 but also to maintain bracket 11 in related assembly with panel 10 through the frictional engagement of panel 18 and panel 10 with opposite sides of flange 12. The enlarged apertures which may if desired be filled with suitable insulating washers are to preclude any electrical contact between flange 12 and screws 17 which, it will be seen, are in electrical engagement with members 15 and 16. Members 15 and 16 bear on their adjacent surfaces opposed contacts 19 and 20, the separation of which serves to break a circuit for a purpose to be hereinafter described. Adjacent the extremities of contact members 15 and 16 and supported by bracket 11 is a pivot pin 21, which has mounted thereon a manually operable lever 22, comprised of insulating material to preclude interference with a circuit through arms 15 and 16. Lever 22 has an arcuate portion 23 at an extremity thereof, adapted, under certain circumstances, to abut an upwardly extending portion 24 of contact member 16. Also carried by pin 21 is a bracket member 25, which has a lateral extension 26 and a vertically extending portion 27 (see Figure 3). Extension 27 is adapted to be engaged, under certain circumstances, by a projection 28 of member 22. Bracket member 25 also has rigidly associated therewith a circular portion 29 also comprised of insulating material. A mounting member 30 is connected to bracket 11, as by a screw 31 and a screw 32 in a slot 33 which latter permits adjustment

30
35
40
45
50

of the assembly with respect to extension 26. Two bimetallic strips 34 and 35, secured together as by a stud 36, are suitably secured to mounting member 30. Mounted adjacent member 35 is a resistance element comprised of a coil 37 having wires 38 leading thereto from suitable terminals 39 carried by a depending insulating panel 40, secured in any desired manner to bracket 11. Rigidly secured to the free end of bimetal strip 35 and on the opposite side of coil 37 is a third bimetal element 41, which has, as better shown in Figures 3 and 4, an upwardly extending portion 42 adapted, under certain circumstances to be set forth hereinafter, to engage extension 26.

The disposition of the component metals of strips 34 and 35 is opposite in order that a change in temperature value applied equally to both will cause a balancing movement of the two strips in opposite directions. In other words, the positioning of strips 34 and 35 is designed to overcome the effect of ambient temperature changes on the assembly. Resistance 37 is positioned, as above stated, adjacent strip 35 and heat therefrom accordingly affects strip 35 more strongly than strip 34 to overcome the compensating effect. Element 41 is so arranged that temperature change will occasion movement thereof corresponding to the movement of strip 35 and since heat from resistance 37 is supplied to both strips 35 and 41, such temperature rise will by the multiplication of energy occasioned by the two elements readily overcome any resistance offered by element 34.

In operation, when a circuit passes through coil 37 the bimetal assembly comprised of elements 34, 35, and 41 tends to expand and the arrangement, as above stated, is such that such expansion causes the assembly to move in a direction away from contact carrying members 15 and 16. Upon such motion, portion 42 will move beyond the end of extension 26, which, due to the spring pressure exerted on portion 29 by spring contact carrying member 16, will immediately drop into the position shown in Figure 3, which permits contacts 19 and 20 to separate and due to the pressures of arcuate portion 23 against extending portion 24 of spring contact arm 16, contact 20 will be precluded from moving with contact 19 as the latter moves away. Extension 26 also serves to hold the bimetal assembly in the position shown in Figure 3 until such time as lever 22 is moved manually to the left, as seen in Figure 2. Upon such motion, projection 28 engages extension 27 and lifts extension 26 out of engagement with projecting portion 42. Since the breaking of contacts 19 and 20 serves to break the circuit through coil 37 the bimetal assembly will cool substantially immediately after the cessation of heat in coil 37 and upon the raising of extension 26 by movement of manual reset lever 22 returns to its normal or closed position. Contacts 19 and 20 close and the device will be ready to repeat the previously described cycle of operation.

It may here be pointed out that due to the configuration of lever 22, contacts 19 and 20 will not close until lever 22 has been manually moved to the left and released whereupon pressure of spring arm 16 and extension 24 against circular member 29 and curved member 23, respectively, will return the switch to its normal right-hand closed circuit position. It will be noted that there is a clearance between projection 28 and extension 27 and that due to this

clearance upon movement of lever 22 to the left, curved portion 23 will first engage extension 24 to move it to the right. After the clearance above mentioned has been closed, projection 28 will engage extension 27, which will in turn move circular member 29 a short distance to the right until such time as extension 26 clears projection 42. Then upon release of lever 22, the spring pressure, as above described, will permit the parts to return to normal position and the contacts 19 and 20 to close.

From the foregoing it will be seen that all stress on the movable parts of the device, such as projection 26 and contact bearing arms 15 and 16 is transmitted directly thereto from lever 22 and that no strain other than normal spring pressure is placed upon contact bearing arms 15 and 16. In other words, movement of lever 22 causes projection 28 to move extensions 27 and 26 and circular member 29 to move contact arm 15, and pressure of arcuate portion 23 against extension 24 causes movement of contact arm 16.

By this means, the resilience of arms 15 and 16 is less apt to be impaired, the life of the switch is lengthened, and more efficient operation assured.

Many modifications of this invention may occur to those skilled in the art, and it is therefore to be distinctly understood that I am not to be limited to the particular embodiment disclosed but rather by the scope of the appended claims.

I claim as my invention:

1. A switch comprising a pair of resiliently mounted contacts, a pair of pivoted levers one end of each engaging one of the contacts to move it against the resilience of its mounting, a one-way driving connection between one of said levers and the other, means for rotating said one lever and hence said other lever through the one-way driving connection, a thermostatic latch for preventing return of said other lever upon release of said first lever, and means for heating said thermostat to cause it to trip the latch.

2. A switch comprising a pair of resiliently mounted contacts, a pair of pivoted levers one end of each engaging one of the contacts to move it against the resilience of its mounting, a one-way driving connection between one of said levers and the other, means for rotating said one lever and hence said other lever through the one-way driving connection, a thermostatic latch for preventing return of said other lever upon release of said one lever thus causing switch closure, and means for heating said thermostat causing it to expand and release the other lever and permit switch opening.

3. A switch comprising a pair of resiliently mounted contacts, a pair of pivoted levers one end of each engaging one of the contacts to move it against the resilience of its mounting, a one-way driving connection between one of said levers and the other, means for rotating said one lever and hence said other lever through the one-way driving connection, a bimetallic blade having an end engaging said other lever under normal temperatures of said blade thus preventing its return upon release of said one lever causing switch closure, and means for heating said bimetallic blade to cause it to flex from engagement with said other lever to permit it to rotate and open the switch.

4. A switch comprising a pair of resiliently mounted contacts, a pair of pivoted levers one end of each engaging one of the contacts to move

it against the resilience of its mounting, a one-way driving connection between one of said levers and the other, means for rotating said one lever and hence said other lever through the one-way driving connection, a thermostatic latch for preventing return of said other lever upon release of said first lever thus causing switch closure, said latch comprising two bimetallic thermostatic elements connected together at one end to form a generally U-shaped member, the other end of the first thermostatic element being connected to a support and the other end of the second thermostatic element engaging said second lever, and heating means disposed between the two thermostats to heat them both and cause them to bend in the same direction to cause the second element to release the second lever to cause switch opening.

5. A switch comprising a pair of resiliently mounted contacts, a pair of pivoted levers one end of each engaging one of the contacts to move it against the resilience of its mounting, a one-way driving connection between one of said levers and the other, means for rotating said one lever and hence said other lever through the one-way driving connection, a thermostatic latch for preventing return of said other lever upon release of said first lever thus causing switch closure, said latch comprising two bimetallic thermostats connected together at one end to form a generally U-shaped member and being arranged to flex in the same direction on temperature change, one end of the first thermostat being connected to one end of a third bimetallic thermostat mounted on a support at its other end and arranged to flex in the opposite direction from the other two and of a size to just compensate them for changes in ambient temperature, the other end of said second thermostat engaging said second lever, and heating means disposed between the first and second thermostats to heat them and cause them to bend in a direction to cause the second thermostat to release the second lever and cause switch opening.

6. A switch comprising a pair of resiliently mounted contacts, a pair of pivoted levers one end of each engaging one of the contacts to move it against the resilience of its mounting, a one-way driving connection between one of said levers and the other, means for rotating said one lever and hence said other lever through the one-way driving connection, a thermostatic latch for preventing return of said other lever upon release of said first lever thus causing switch closure, said latch comprising two bimetallic thermostats connected together at one end to form a generally U-shaped member and being arranged to flex in the same direction on temperature change, one end of the first thermostat being connected to one end of a third bimetallic thermostat mounted on a support at its other end and arranged to flex in the opposite direction from the other two and of a size to just compensate them for changes in ambient temperature, the other end of said second thermostat engaging said second lever, and heating means disposed between the first and second thermostats to heat them and cause them to bend in a direction to cause the second thermostat to release the second lever and cause switch opening, the support of said third thermostat comprising a plate mounted for rotation about a pivot so that the thermostatic latch assembly may be adjusted relatively to the two levers.

7. A switch comprising a pair of resiliently

mounted contacts, a pair of pivoted levers one end of each engaging one of the contacts to move it against the resilience of its mounting, a one-way driving connection between one of said levers and the other, means for rotating said one lever and hence said other lever through the one-way driving connection, a first thermostat mounted at one end on a support and connected at its other end to one end of a second thermostat the other end of which engages said other lever for preventing its return upon the release of said first lever, said first thermostat being arranged to respond oppositely to said second thermostat in order to compensate it for changes in ambient temperature, and means for heating said second thermostat to cause it to disengage said other lever.

8. A switch comprising a pair of resiliently mounted contacts, a pair of pivoted levers one end of each engaging one of the contacts to move it against the resilience of its mounting, a one-way driving connection between one of said levers and the other, means for rotating said one lever and hence said other lever through the one-way driving connection, a first bimetallic thermostat having one end cooperating with said other lever under normal temperatures thus preventing its return upon release of said first lever thus causing switch closure, a second bimetallic thermostat connected at one end to the other end of said first thermostat and adapted to flex in the opposite direction therefrom on temperature change, said second thermostat being mounted on an adjustable plate, and means for heating said first thermostat to cause it to flex from engagement with said other lever to permit it to rotate and open the switch.

9. A switch comprising a pair of leaf springs each carrying an electrical contact, said contacts being in spaced relation when the leaf springs are in their normal position, a first lever having one end adjacent one of the leaf springs, a second lever having a one-way drive connection with the first lever and having one end adjacent the other leaf spring, manual means for rotating the second lever and hence the first lever through the one-way drive connection causing both leaf springs to move in unison and maintain the contacts spaced apart, latch means for preventing reverse movement of said first lever after a predetermined rotation thereof, said other leaf spring causing said second lever to reverse upon release thereof which causes the electrical contacts to engage, and means for tripping the latch to cause said contacts to open.

10. A switch comprising a pair of leaf springs each carrying an electrical contact, said contacts being in spaced relation for normal positions of said leaf springs, a first lever having an extension on one of its arms, its other arm lying in contact with one of the leaf springs, a second lever having a projection lying adjacent said extension and having one end lying in contact with the other of the leaf springs, a handle on said second lever forming a manual means for rotating it and the first lever through the projection and extension, said levers causing said leaf springs to bend in unison in the same direction maintaining the contacts in spaced relation, latch means tensioned to move into the path of said first lever after a predetermined rotation thereof, the other of said leaf springs causing reversal of said second lever upon release thereof, reversal of said first lever being prevented by said latch thereby causing said switch contacts

to close, means to trip said latch, and stop means for limiting the manual rotation of said second lever in one direction and the rotation of said second lever by said other leaf spring in the other direction.

11. A switch operating mechanism comprising, two resiliently mounted electrical contacts, a thermostat, a pivoted lever one end of which engages said thermostat and the other end of which engages the first of said contacts to hold it in switch closing position against the resilience of its mounting, means for heating said thermostat to cause it to flex in a direction to release said lever thus permitting the switch contact to move to open contact position and to rotate said lever about its pivot, a second lever having a portion adapted to engage the second switch contact and another portion adapted to contact the first lever, and means for rotating said second lever to cause rotation of the first lever and hence cause movement of both switch contacts simultaneously in the same direction, release of said second lever permitting said second switch contact to reverse its rotation and to cause switch closure providing the thermostat has cooled enough to engage the first lever and prevent its reversal.

12. A switch comprising a pair of resiliently mounted contacts, a pair of pivoted levers one end of each engaging one of the contacts to move it against the resilience of its mounting, a one-way driving connection between one of said levers and the other, means for rotating said one lever and hence said other lever through the one-way driving connection, a thermostatic latch for preventing return of said other lever upon release of said one lever thus causing switch closure, means for heating said thermostat causing it to expand and release the other lever and permit switch opening, and means for adjusting the amount of heat necessary to cause the thermostat to trip the latch.

13. A switch comprising a pair of resiliently mounted contacts, a pair of pivoted levers one end of each engaging one of the contacts to move it against the resilience of its mounting, a one-way driving connection between one of said levers and the other, means for rotating said one lever and hence said other lever through the one-way driving connection, a thermostatic latch for preventing return of said other lever upon release of said first lever thus causing switch closure, said latch comprising two bimetallic thermostatic elements connected together at one end to form a generally U-shaped member, the other end of the first thermostatic element being connected to a support and the other end of the second thermostatic element engaging said second lever, heating means disposed between the two thermostatic elements to heat them both and cause them to bend in the same direction to cause the second element to release the second lever to cause switch opening, means for mounting said thermostatic elements on the same support and means for adjusting said support.

14. A switch comprising a pair of resiliently mounted contacts, a pair of pivoted levers one end of each engaging one of the contacts to move it against the resilience of its mounting, a one-way driving connection between one of said levers and the other, means for rotating said one lever and hence said other lever through the one-way driving connection, a thermostatic latch for preventing return of said other lever upon release of said first lever thus causing switch

closure, said latch comprising two bimetallic thermostats connected together at one end to form a generally U-shaped member and being arranged to flex in the same direction on temperature change, one end of the first thermostat being connected to one end of a third bimetallic thermostat mounted on a support at its other end and arranged to flex in the opposite direction than the other two and of a size to just compensate them for changes in ambient temperature, the other end of said second thermostat engaging said second lever, heating means disposed between the first and second thermostats to heat them and cause them to bend in a direction to cause the second thermostat to release the second lever and cause switch opening, and means for adjusting the amount of heat necessary to cause the second thermostat to release the second lever.

15. A switch comprising a pair of leaf springs each carrying an electrical contact, said contacts being in spaced relation when the leaf springs are in their normal position, a first lever having one end adjacent one of the leaf springs, a second lever having a one-way drive connection with the first lever and having one end adjacent the other leaf spring, manual means for rotating the second lever and hence the first lever through the one-way drive connection causing both leaf springs to move in unison and maintain the contacts spaced apart, latch means preventing reverse movement of said first lever after a predetermined rotation thereof by said second lever, said other leaf spring causing said second lever to reverse upon release thereof which causes the electrical contacts to engage, means for automatically tripping the latch after a predetermined time to cause said contacts to open, and means for adjusting the time necessary for tripping the latch.

16. A thermal cut-out comprising a pair of leaf springs, a contact carried by each, a retainer for biasing one of said leaf springs to position with its contact engaging the other contact, a bimetal latch for said retainer, said latch upon releasing said retainer permitting one of said leaf springs to move to position with the contact carried thereby out of engagement with the other contact, a heating element for so unlatching said latch upon predetermined current flow through said heating element and manual means for relatching said retainer, said means being engageable with said retainer to move it to latched position and simultaneously engageable with said other leaf spring to move it in a direction separating the contact carried thereby from the contact carried by one of said leaf springs.

17. A thermally operated current responsive switch of the class described, comprising, in combination, a support, a first spring contact blade having one of its ends fixedly secured thereto, a second spring contact blade also having one of its ends fixedly secured to said support near the fixed end of said first spring contact blade and extending substantially parallel to said first blade, said spring contact blades being normally biased to open circuit position, locking means to hold said contact blades in closed circuit position including a thermally responsive means which if removed renders said locking means ineffective to hold said contact blades in closed circuit position, said locking means being adapted to release said contact blades for movement to open circuit position at a predetermined temperature, and manual means for moving said contact

blades to locking position after they have been released, said manual means maintaining said contact blades in open circuit relation during the locking operation.

18. A thermally operated current responsive switch of the class described comprising a pair of electrical contact carrying blades each anchored at one end and biased away from each other to normally open the contacts, a bimetal strip thermal element and means for operatively associating the thermal bimetal strip element with the contacts to normally afford endwise resistance by the bimetal strip to opening movement of the contacts, warping movement of the

bimetal strip under influence of heat shifting the end of said bimetal strip to permit the contacts to open under their normal bias, the parts being so arranged that upon removal or breakage of the bimetal strip the contacts will separate, and means for resetting said contacts to closed position comprising a movable member separately moving each of said contact blades to retain them separated until the thermal bimetal strip has been endwise engaged to retain one of said contact blades in its reset position before the other contact blade is permitted to engage therewith.

ERNEST M. MILLER.
